(57) **CLAIM**

The ornamental design for a magnetic field generating device for use in magnetic resonance imaging, as shown and described.

DESCRIPTION

FIG. 1 is a perspective view of a magnetic field generating device for use in magnetic resonance imaging showing a first embodiment of our new design;

FIG. 2 is a front view thereof, the opposite side being a mirror image of the side shown herein;

FIG. 3 is a left side view thereof, the opposite side being a mirror image of the side shown herein;

FIG. 4 is a top view thereof;

FIG. 5 is a bottom view thereof;

FIG. 6 is a perspective view of a magnetic field generating device for use in magnetic resonance imaging showing a second embodiment of our new design;

FIG. 7 is a front view thereof, the opposite side being a mirror image of the side shown herein;

FIG. 8 is a left side view thereof, the opposite side being a mirror image of the side shown herein;

FIG. 9 is a top view thereof; and,

FIG. 10 is a bottom view thereof.
